[57] **CLAIM**

The ornamental design for jaws for folding pliers, as shown
and described.

DESCRIPTION

FIG. 1 is an isometric view from the upper left rear of a pair
of jaws for folding pliers showing my new design, wherein
the broken line depiction of a pair of handles is included for
illustrative purposes and forms no part of the claimed
design;

FIG. 2 is a top plan view of the jaws for folding pliers shown
in FIG. 1;

FIG. 3 is a left side elevational view thereof;

FIG. 4 is a front, or jaw tip, end elevational view thereof;

FIG. 5 is a rear ends elevational view thereof;

FIG. 6 is a bottom plan view thereof; and,

FIG. 7 is a right side elevational view thereof.
